UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,322,317.

Specification of Letters Patent. Patented Nov. 18, 1919.

Application filed December 4, 1917. Serial No. 205,429.

To all whom it may concern:

Be it known that I, RONALD A. McCANN, a citizen of the United States, residing at Swissvale, in the county of Allegheny and 5 State of Pennsylvania, have invented certain new and useful Improvements in Railway Signaling, of which the following is a specification.

My invention relates to railway signaling, 10 and particularly to signaling for single track over which traffic moves in both directions. More specifically, my invention relates to means for controlling the signals adjacent the passing sidings in systems of 15 the type specified.

I will describe two forms of signaling embodying my invention, and will then point out the novel features thereof in claims.

In the accompanying drawings, Figure 1 20 is a view showing one arrangement of signals to which my invention may be applied. Fig. 2 is a diagrammatic view showing one arrangement of apparatus and circuits for the control of signal 5 in Fig. 1 and embodying my invention, the arrangement shown in this view being particularly well adapted to systems employing direct current as the controlling and operating energy. Fig. 3 is a diagrammatic view showing a 25 modification of the apparatus and circuits shown in Fig. 2 and also embodying my invention, the arrangement shown in this view being particularly well adapted to signaling systems in which alternating current is the 30 controlling and operating energy.

Similar reference characters refer to similar parts in each of the several views.

Referring first to Fig. 1, the reference character 15 designates the track rails of a 40 portion of a single track railway, which is divided by passing sidings M, N and O into two stretches A—D and E—H. Stretch A—D is further divided by insulated joints 2, into a number of blocks, A—B, B—C and 45 C—D, while stretch E—H is similarly divided into blocks E—F, F—G and G—H.

Traffic through the stretch E—H from 50 east to west is governed by a plurality of signals 1, 3 and 5, while traffic through this same stretch in the opposite direction is governed by signals 4, 6 and 8. Stretch A—D is similarly provided with signals 9, 11, 13, 12, 14 and 16. The passing siding N is protected by signals 7 and 10. As here shown,

a pair of opposing signals is located adjacent each end of each block, although I do not desire to be limited to this particular location and distribution of the signals.

The signals for stretch A—D are so controlled that when a train moving toward the 60 east enters this stretch, signal 9 is placed at "stop" and is held there until the train passes out of the stretch, thus prohibiting a westbound train from entering the stretch while the stretch is occupied by the east- 65 bound train. As the eastbound train enters the stretch, it also causes signal 16 to indicate "stop", and as it passes signals 14 and 12 these signals are similarly caused to change to "stop" indication. When the entire train passes out of block A—B, signal 16 changes to the "caution" indication, and when the entire train passes out of block B—C, this signal returns to the full "proceed" indication. Signal 14 changes to 70 "caution" when the train leaves block B—C, and to "proceed" when the train leaves block C—D. Two or more trains may, therefore, follow each other through the stretch under the same signal protection 75 as is customarily provided on double track roads. Similarly, when a westbound train enters stretch A—D, signals 9, 12, 14 and 16 are placed at stop, and signal 9 subsequently changes successively to caution and proceed. 80 Signal 11 changes to stop when it is passed by the train, and subsequently changes to 85 caution and proceed successively.

The signals for stretch E—H are controlled in the same manner as the signals for 90 stretch A—D.

The operation of the signals which I have just outlined may be accomplished by several different arrangements of apparatus and circuits, such, for example, as the arrangements shown in Letters Patent of the United States Nos. 1,204,998 and 1,233,488, granted to me on November 14, 1916, and on July 17, 1917, respectively. I do not wish to be limited, however, to any particular arrangements of apparatus and circuits for accomplishing this signal operation.

Whenever signal 9 indicates stop, signal 7, of course, indicates "caution," and whenever signal 7 indicates "stop," signal 5 indicates "caution." The manner in which this control is accomplished will be explained hereinafter. It is desirable, however, that

when an eastbound train occupies stretch A—D, signal 5 as well as signal 7 should indicate caution, but that when a westbound train has passed signal 9, thus allowing signal 7 to change to caution, signal 5 should return to the full proceed position. The reason for this is as follows: Assume that signal 5 indicates proceed while signal 9 is at stop, and that two trains moving in opposite directions approach siding N. If the eastbound train should pass signal 9 just after the westbound train had passed signal 5 (indicating proceed), the westbound train would receive a stop indication at signal 7 without having been previously warned by a caution indication at signal 5. However, if two westbound trains are moving along the track between A and H, it is desirable that signal 5 should change to proceed indication as soon as the first train has passed signal 9, in order to avoid any unnecessary delay to the second train by a caution indication at signal 5.

The object of the present invention is the provision of novel and simple means for accomplishing the desired control of signal 5.

Referring now to Fig. 2, the main track of the siding N is provided with a track circuit comprising a battery b^{10} and a track relay T^{10} . Block E—F is divided into two sections E—K and K—F, each of which is provided with a track circuit comprising batteries b^8 and b^5 and track relays T^8 and T^5 .

Signal 7 is controlled by a signal relay R^7 , which is responsive to reversals of current. The "caution" indication circuit for this signal is from battery Z^7 through wires 17, 18, 19 and 20, neutral contact 21 of relay R^7 , wire 22, signal 7, wire 23, neutral contact 24 of relay R^7 , and wires 25, 26, 27 and 28 to battery Z^7 . The "proceed" indication circuit for this signal is the same as the caution circuit up to and including contact 21, then through wire 29, polarized contact 30, wire 31, signal 7, thence as before to battery Z^7 . Signal 7, consequently, indicates "proceed" when relay R^7 is energized in such direction as to close contact 30 (which I will call the normal direction of energization), "caution" when the relay is energized in the reverse direction, and "stop" when the relay is deenergized.

Signal 5 is similarly controlled by a signal relay R^5 , the caution circuit for this signal including neutral contacts 32 and 33, and the proceed circuit including a contact 34 which is closed when the relay is energized in normal direction but not in reverse direction.

Signal relay R^7 is provided with a circuit which is controlled by the track relay T^{10} and by a pole-changer W operated by signal 9, this pole-changer being reversed while the signal is moving between the stop and cau-

tion positions. This circuit, when the pole-changer is in the position shown, is from battery Z^9 through wire 35, pole-changer W, wires 36 and 37, contact 38, wire 39, relay R^7 , wire 40, pole-changer W, wire 41 to battery Z^9 . When signal 9 indicates proceed or caution, relay R^7 is energized in the normal direction so that signal 7 then indicates proceed; but when signal 9 indicates stop, relay R^7 is energized in the reverse direction, so that signal 7 then indicates caution; assuming, of course, that block D—E is unoccupied.

Signal relay R^5 is provided with a circuit which is controlled by a pole-changing relay P, the contacts of which constitute a pole-changer for reversibly connecting relay R^5 with battery Z^7 according as relay P is energized or deenergized. When this relay P is energized, as shown, the circuit for relay R^5 is from battery Z^7 through wires 17, 18 and 44, contact 42, wire 45, contact 46 of track relay T^8 , wire 47, contact 48 of track relay T^8 , wire 49, relay R^5 , wire 50, contact 43, wires 51 and 28 to battery Z^7 . When relay P is energized, relay R^5 is energized in normal direction so that signal 5 indicates "proceed"; but when relay P is deenergized, relay R^5 is energized in reverse direction, so that signal 5 indicates "caution"; assuming, of course, that block E—F is unoccupied.

Pole-changing relay P is provided with a circuit which is from battery Z^7 through wires 17, 18, 19 and 20, contact 21, wire 29, contact 30, wire 52, contact 53^N of a relay J, wire 54, contact 55, wire 56, relay P, wires 57, 27 and 28 to battery Z^7 . Contact 55 is operated by signal 7 and is closed while this signal is in clear or caution position or at any point between these two positions. Assuming, then, that contact 53^N is closed, relay P will be energized when relay R^7 is energized in normal direction but not when energized in the reverse direction, this selection being accomplished by polar contact 30 of relay R^7 .

It follows from the foregoing that with only the apparatus thus far described, whenever signal 9 indicates stop, signal 5 will indicate caution, because relay P will be deenergized due to the reverse energization of relay R^7 .

Relay P is provided with another or auxiliary circuit, which is controlled by contact 53^R of relay J, this circuit being from battery Z^7 through wires 17 and 58, contact 53^R, wire 54, contact 55, wire 56, relay P, wires 57, 27 and 28 to battery Z^7 . Consequently, when contact 53^R is closed, relay P will be energized when relay R^7 is reversely energized (contact 55 being closed when signal 7 indicates caution), and so signal 5 may then indicate proceed while signal 9 indicates stop.

Relay J is a directional relay, its contact 130

53^N or 53^R being closed according as the relay is energized in normal or reverse direction. Furthermore, when either contact is closed such contact remains closed until the 5 relay is subsequently energized in the opposite direction, even though the relay may in the meantime become deenergized. This 10 relay is provided with a reverse energizing circuit which is from the right-hand terminal of battery Z^r through wires 28, 27, 26 and 59, contact 60, wire 61, back point of contact 62, contact 63, wire 64, relay J, wire 65 to middle point of battery Z^r. This 15 circuit is closed momentarily when a train moving toward the west enters block D—E, because the back point of contact 62 of relay R^r then closes and contact 60 is closed momentarily while signal 7 is moving toward stop position.

20 Relay J is also provided with a normal energizing circuit for restoring its contact to the position shown, this circuit being from the left-hand terminal of battery Z^r through wires 17, 18, 19 and 66, contact 67, wire 68, 25 front point of contact 62, contact 63, wire 64, relay J, wire 65 to the middle point of battery Z^r. Contact 67 is closed when signal 7 indicates caution, hence this circuit is closed momentarily when relay R^r becomes 30 energized in normal direction and before signal 9 leaves the caution position, that is, when the westbound train passes signal 11 in Fig. 1.

The operation of the system shown in 35 Fig. 2 is as follows:

When there is no train on the track between points A and F in Fig. 1, the parts of the apparatus are in the positions in which they are shown in Fig. 2, so that signals 9, 7 and 5 indicate "proceed". If, now, 40 a train moving toward the east enters stretch A—B, it causes signal 9 to change to "stop" indication. This movement of signal 9 reverses pole-changer W so that signal relay R^r becomes energized in the reverse direction, thus causing signal 7 to change to "caution" position. This reversal of relay R^r causes pole changing relay P to become deenergized because of the opening 45 of contact 30, thus reversing the direction in which relay R^s is energized whereby signal 5 changes to the "caution" position. The signals remain in these positions until the train enters block D—E, whereupon signal 5 50 changes to the "stop" position because relay R^r becomes deenergized due to the opening of contact 38 or track relay T¹⁰. As the train enters block E—F, signal 5, of course, changes to the "stop" position, due to the 55 opening of relay R^s.

I will now assume that the track between A and F is unoccupied and that a train moving toward the west enters block E—F. The consequent opening of track relay T^s 60 causes relay R^s to become deenergized

whereby signal 5 changes to the "stop" position. As the train proceeds through the block E—F, track relay T^s opens and track relay T^r closes, but this causes no change in the condition of the apparatus. As the 70 train enters the block D—E, it opens track relay T¹⁰, which in turn deenergizes relay R^r whereby signal 7 changes to the "stop" position. During this movement of signal 7, contact 60 is closed momentarily, thus 75 closing the reverse energization circuit for relay J. Contact 53^R of this relay then becomes closed instead of 53^N. When the entire train has passed out of the block E—F, track relay T^s closes, thus causing relay R^s 80 to become energized, but this relay is then energized in the reverse direction because relay P is deenergized, due to the fact that its circuit is opened at contact 55. Signal 5, therefore, assumes the "caution" position. 85 As the train passes into block C—D it causes signal 9 to change to the "stop" position, so that when track relay T¹⁰ closes, relay R^r becomes energized in the reverse direction, thus causing signal 7 to move to 90 the "caution" position. Contact 55 then becomes closed, thus closing the auxiliary circuit for relay P because this circuit does not include contact 30 of relay R^r. The consequent energization of relay P causes relay R^s 95 to be energized in the normal direction, so that signal 5 changes to the "proceed" position. When the train passes signal 11 in Fig. 1, signal 9 moves to "caution," and the consequent reversal of pole-changer W 100 causes relay R^r to become energized in the normal direction. The normal energizing circuit for relay J is then closed momentarily at contacts 67, 62 and 63, so that this relay is restored to its normal position 105 wherein contact 53^N is closed. The reversal of relay R^r causes signal 7 to change to the "proceed" position. The parts of the apparatus are then in the positions in which they are shown in the drawing, except that signal 9 is at "caution." This signal, of course, 110 will change to the "proceed" position as soon as the train passes signal 13 in Fig. 1.

Referring now to Fig. 3, the system here shown is similar to that shown in Fig. 2, 115 except for certain changes which are desirable on account of the substitution of sources of alternating current for the batteries shown in Fig. 2. It is understood that the primary winding of each transformer U', U^s, U^r and U⁹ shown in Fig. 3 is connected with a suitable source of alternating signaling current. The two track circuits for block E—F in Fig. 2 are replaced by a single center-fed track circuit in Fig. 3, the 120 source of current for such track circuit being transformer U'. As for block D—E, the single track circuit shown in Fig. 2 is replaced by a center-fed track circuit in Fig. 3, thus introducing an additional track re- 125 130

lay T^7 having a contact 38^a included in the circuit of signal relay R^7 . The source of current for this track circuit is a transformer X , the primary of which is connected with the secondary of transformer U^7 , the primary circuit of transformer X including switch-operated contacts 83 and 84 for a purpose hereinafter explained.

Signal relay R^7 comprises a pair of contacts 21 and 24 which are swung to the right or left according as the relay is energized in the normal or the reverse direction, and which occupy intermediate positions when the relay is deenergized. The caution indication circuit for signal 7 is closed when relay R^7 is energized in the reverse direction, this circuit being from secondary of transformer U^7 through wires 17, 18, 19 and 20, left-hand point of contact 21, wire 29, signal 7, wire 23, left-hand point of contact 24, wires 25, 26, 27 and 28 to the secondary of transformer U^7 . The proceed indication circuit for this signal is closed when relay R^7 is energized in the normal direction, this circuit being from transformer U^7 through wires 17, 18, 19 and 20, right-hand point of contact 21, wire 22, signal 7, wire 23, right-hand point of contact 24, wires 25, 26, 27 and 28 to transformer U^7 .

Signal 5 is controlled in a similar manner by signal relay R^5 .

Relay P is provided with a circuit which passes from the secondary of transformer U^7 through wires 17, 18, 19, 20 and 78, right-hand point of contact 79 of relay R^7 , wire 85, back point of contact 69 of relay J^a , wire 54, contact 55, wire 56, relay P, and wires 57 and 28 to transformer U^7 . Assuming, then, that the back point of contact 69 is closed, and that contact 55 is closed, relay P will be energized when relay R^7 is energized in normal direction but not when relay R^7 is energized in the reverse direction, this selection being accomplished by contact 79 of relay R^7 . Relay P is provided with an auxiliary circuit, which is closed only when relay J^a is energized, this circuit being from transformer U^7 through wires 17, 18 and 70, front point of contact 69, wire 54, contact 55, wire 56, relay P and wires 57 and 28 to transformer U^7 . Consequently, when relay J^a is energized and contact 55 is closed, relay P will be energized if relay R^7 is reversely energized, and so signal 5 may then indicate "proceed" while signal 9 indicates "stop."

Relay J^a is provided with an energizing circuit which passes from the secondary of transformer U^7 through wires 17, 18, 19, 71 and 72, contact 73, wire 74, back point of contact 75 of track relay T^7 , wire 76, relay J^a , wires 77, 27 and 28 to transformer U^7 . This circuit will be closed when a train moving toward the west enters block D-E, but will

immediately be opened at contact 73 when signal 7 moves away from the proceed position. Relay J^a when once energized, is held energized by a holding circuit which is from transformer U^7 through wires 17, 18, 19, 20 and 78, contact 79, wire 80, contact 81, wire 82, relay J^a and wires 77, 27 and 28 to transformer U^7 . This circuit is closed at contact 79 when relay R^7 is deenergized or is energized in the reverse direction.

The operation of the system shown in Fig. 3 is similar to that shown in Fig. 2; consequently, a few brief remarks concerning this operation will be sufficient. As a train moving toward the east enters stretch A-D in Fig. 1, the consequent movement of signal 9 to danger position reverses the direction of energization of relay R^7 and so opens at contact 79 the circuit for relay P. The deenergization of relay P, of course, reverses the direction of energization of relay R^5 so that signal 5 moves to the caution position.

When a train moving toward the west enters block D-E, it opens track relay T^7 and so closes the energizing circuit for relay J^a . As soon as contact 79 of relay R^7 reaches its intermediate or deenergized position, the holding circuit for relay J^a is closed. Consequently, when the train passes out of block D-E and signal 7 has moved to the caution position, relay P becomes energized so that signal 5 moves to the proceed position. After the train passes signal 11 in Fig. 1, relay R^7 becomes energized in the normal direction so that contact 79 opens the holding circuit for relay J^a whereupon this relay becomes deenergized.

As has been pointed out hereinbefore, the primary circuit for transformer X is controlled by switch operated contacts 83 and 84. Contact 83 is operatively connected with switch 86 and is closed when this switch is set for the straight track but opened when the switch is set for the siding. Contact 84 is similarly operated by switch 85. The reason for including these contacts in the transformer circuit is as follows: First, assuming that the primary of transformer X were always connected with a source of current and that a train moving toward the west enters the siding N, it will be seen that when such train occupies the portion of the siding between points 2^a and 2^b, relay J^a would become deenergized. Then, if the train should proceed out on the main track through switch 86 and pass signal 9, relay J^a would continue to be deenergized so that signal 5 would be held in the caution position until the train passes signal 11 in Fig. 1. By including contact 83 in the circuit for transformer X , the operation becomes as follows: As the westbound train enters the siding and passes beyond point 2^b, relay J^a becomes deenergized, but when switch 86 is reversed to allow this train to pass out on

to the main track, track relay T' becomes de-energized and so closes the energizing circuit for relay J^a. Relay R' is, of course, then de-energized so that the holding circuit for relay J^a is closed. It follows, then, that after the train passes signal 9, relay P will become energized so that signal 5 will move to the proceed position.

Where in the accompanying claims I have

- 10 used the expression "a portion of railway track comprising three successive blocks", the blocks referred to are blocks E—F, D—E and C—D, these blocks being the first, second and third blocks respectively. The 15 "signals for the first and second blocks" are signals 5 and 7 respectively.

Although I have herein shown and described only two forms and arrangements of apparatus and circuits embodying my invention, it is understood that various changes and modifications may be made therein within the scope of the appended claims without departing from the spirit and scope of my invention.

- 25 Having thus described my invention, what I claim is:

1. In combination, a portion of railway track comprising three successive blocks, a first and a second signal for the first and 30 second blocks respectively, a signal relay for controlling said second signal, a stick relay, means controlled by said signal relay and by a train passing along said track from the first block toward the third for energizing 35 said stick relay and holding it energized until the train leaves the third block, said stick relay remaining de-energized during the passage of a train in the other direction, and means controlled by said stick relay and by 40 said signal relay and operating when the signal relay is in such condition that the second signal indicates caution to cause the first signal to indicate proceed or caution according as the stick relay is energized or de-45 energized.

2. In combination, a portion of railway track comprising three successive blocks, a first and a second signal for the first and second blocks respectively, a first and a second signal relay for controlling said first and second signals respectively and each responsive to reversals of current whereby each signal indicates proceed or caution according as the corresponding signal relay is energized in normal or reverse direction, train-controlled means for causing the second signal relay to be energized in reverse or normal direction according to the presence or absence of a train in the third section, a pole-changing relay for controlling the signal relay for the first signal whereby such signal relay is energized in normal or reverse direction according as the pole-changing relay is energized or de-energized, a directional 60 relay controlled by train movements and oc-

cupying a normal position when the second and third blocks are unoccupied but a reverse position while a train moving in the direction of traffic governed by said signals occupies the second and third blocks, and 70 means controlled by said directional relay and said second signal relay for energizing said pole-changing relay only when the second signal relay is energized in normal direction if the directional relay is normal, but 75 for energizing the pole-changing relay when the second signal relay is reversely energized if the directional relay is reversed.

3. In combination, a portion of railway track comprising three successive blocks, a 80 first and a second signal for the first and second blocks respectively, a first and a second signal relay for controlling said first and second signals respectively and each responsive to reversals of current whereby each signal indicates proceed or caution according as the corresponding signal relay is energized in normal or reverse direction, train-controlled means for causing the second signal relay to be energized in reverse or normal direction according to the presence or absence of a train in the third block, a pole-changing relay for controlling the signal relay for the first signal whereby such signal relay is energized in normal or reverse direction according as the pole-changing relay is energized or de-energized, means controlled by the second signal relay for energizing the pole-changing relay when the second signal 85 relay is energized in normal direction but 90 not when it is energized in reverse direction whereby the presence of a train upon the third block moving toward the first will cause the first signal to indicate caution, and means controlled by a train moving in the other direction for causing said pole-changing relay to be energized when the second signal relay is energized in reverse direction whereby when such latter train occupies the 95 third block the first signal will indicate proceed.

4. In combination, a portion of railway track comprising three successive blocks, a first and a second signal for the first and second blocks respectively, a first and a second signal relay for controlling said first and second signals respectively and each responsive to reversals of current whereby each signal indicates proceed or caution according as the corresponding signal relay is energized 115 in normal or reverse direction. train-controlled means for causing the second signal relay to be energized in reverse or normal direction according to the presence or absence of a train in the third section, a pole-changing relay for controlling the signal relay for the first signal whereby such signal relay is energized in normal or reverse direction according as the pole-changing relay is energized or de-energized, means controlled 120

125

130

- by the second signal relay for energizing the pole-changing relay when the second signal relay is energized in normal direction but not when it is energized in reverse direction
- 5 5. whereby the presence of a train upon the third block moving toward the first will cause the first signal to indicate caution, a stick relay, means controlled by said stick relay when energized for causing said pole-
- 10 changing relay to be energized when the second signal relay is energized in reverse direction, and means controlled by a train moving in the direction of traffic governed by said signals for energizing said stick relay when
- 15 15. the train enters the second block and for keeping it energized while the train occupies the second and third blocks, whereby when such latter train occupies the third block the first signal will indicate proceed.
- 20 20. 5. In combination, a portion of railway track comprising three successive blocks, a first and a second signal for the first and second blocks respectively, a first and a second signal relay for controlling said first
- 25 25. and second signals respectively and each responsive to reversals of current whereby each signal indicates proceed or caution according as the corresponding signal relay is energized in normal or reverse direction, train-
- controlled means for causing the second signal relay to be energized in reverse or normal direction according to the presence or absence of a train in the third block, a pole-changing relay for controlling the signal relay for the first signal whereby such signal relay is energized in normal or reverse direction according as the pole-changing relay is energized or deenergized, means controlled by the second signal relay for energizing the pole-changing relay when the second signal relay is energized in normal direction but not when it is energized in reverse direction whereby the presence of a train upon the third block moving toward the first will cause the first signal to indicate caution, a directional relay for causing said pole-changing relay to be energized when the second signal relay is reversely energized, and means controlled by a train moving along said track in the direction in which said signals govern traffic for causing operation of said directional relay.
- 30 35 40 45 50

In testimony whereof I affix my signature in presence of two witnesses.
